FOREIGN PATENT DOCUMENTS

EM 002850040-0001 11/2015

Primary Examiner — Barbara Fox*Assistant Examiner* — Lilyana Bekic(74) *Attorney, Agent, or Firm* — McDonnell Boehnen Hulbert & Berghoff LLP(57) **CLAIM**

The ornamental design for a training injector, as shown and described.

DESCRIPTION

FIG. 1 is a front and left side perspective view of a training injector showing my new design;

FIG. 2 is a front end view of the training injector;

FIG. 3 is a rear end view of the training injector;

FIG. 4 is a left side view of the training injector;

FIG. 5 is a right side view of the training injector;

FIG. 6 is a top view of the training injector; and,

FIG. 7 is a bottom view of the training injector.
